UNITED STATES PATENT OFFICE.

FRANK E. BONHAM, OF ST. PAUL, MINNESOTA.

RAZOR-BLADE SHARPENER.

1,262,008.

Specification of Letters Patent.

Patented Apr. 9, 1918.

Application filed November 3, 1916. Serial No. 129,285.

To all whom it may concern:

Be it known that I, FRANK E. BONHAM, a citizen of the United States, residing at St. Paul, in the county of Ramsey and State of Minnesota, have invented certain new and useful Improvements in Razor - Blade Sharpeners, of which the following is a specification.

My invention relates to improvements in apparatus for sharpening the blades of safety razors, its object being to provide improved means for performing a continuous sharpening operation along the edge of the razor blade, and particularly to impart the tooth-like edge to the blade corresponding to the edge imparted in the ordinary stropping operation of an ordinary razor blade.

To this end the invention consists in the features of construction, combination, and arrangement of parts hereinafter described and claimed.

In the accompanying drawings forming part of this specification, Figure 1 is an elevation of the sharpening members of my apparatus, and supporting frame work thereof.

Fig. 2 is a detail view of one of the sharpening strops.

Fig. 3 is a detail view of a coöperating filling strip.

Fig. 4 is a detail of the adjusting collar for the filling strip and strop.

Fig. 5 is a detail of an opposed collar, and Fig. 6 is a longitudinal, vertical section 35 through the machine as shown in Fig. 1.

Referring to the drawings A represents a suitable frame-work in which a pair of rollers 3, 4 have journal support.

In carrying out my invention I arrange 40 around the roller 3 an endless coil of leather 5, which constitutes one of the strops and around the roller 4 a similar intermeshing leather strop coil 6. An endless filling strip 7, preferably springy, as steel, is wound 45 around each roller to fill the space between the coils of the strops 5 and 6 and hold the coils in uniformly spaced position. Collars 8 and 9 are secured upon the ends of the rollers in abutting position against the corresponding ends of the filling strips 7 and are adjustable upon the rollers to exert pressure against said filling strips to hold the strops 5 and 6 in tightened position against the rollers. The collars are adapted to hold 55 in suitable position the rollers, as by lock screws 10.

The rollers are adapted to be operated by a suitable source of power through the medium of the intermeshing gears 11 connected with the source of power through the pulley 12 and belt 13.

Suitable means may be employed to hold the razor blade in bearing position for stropping against the coil strops 5 and 6. The holding means for the razor blade may be any desired construction as employed in apparatus of this general type and, forming no part of the present invention, is not shown and described.

For the purposes of this application my invention resides in the spiral strops 5 and 6 preferably of leather wound around the rollers, together with the filling strips 7 and the adjustable collars 8 for holding the leather strops between the filling strips. The filling strips and strops are both preferably continuous and as shown the strop upon one roller fits within the spaces formed by the spirals of the strop upon the other roller.

By means of the endless strops 5 and 6 in the spiral coil form shown, a continuous stropping along the edge of the razor blade is secured which imparts a tooth-like effect similar to the effect produced on the edge of an ordinary razor blade by the proper use, 80 of a strop.

By adjusting the collars 8 and 9 inwardly upon the rollers a squeezing pressure is exerted against the adjacent ends of the filling strips to tightly clamp the spiral strop. It will be understood that the spiral strop is loose around the rollers as is the filling strip, being held in position by the clamping collars 8 and 9. On account of the loose 90 positioning of the filling strips and spiral strops clamped within the collars I am enabled to position the leather strop on edge, which gives a much better stropping edge to the razor blade than is given in a construction where the spiral leather coil without intermediate filling strips is permanently positioned around the rollers.

I claim:

1. In an apparatus of the class described, 105 the combination of a pair of rollers, endless stropping coils loosely arranged spirally around said rollers, one coil fitting between the spirals of the coil of the other roller, fillings loosely fitted between the spirals of 110 said coils, and means for holding said coils clamped between said fillings.

2. In an apparatus of the class described, the combination of a pair of rollers, endless intermeshing spiral leather strops coiled around said rollers, spiral filling strips coiled around said rollers between said strops, and means for applying pressure to the adjacent ends of the stropping and filling coils upon each roller for the purpose of

squeezing them together and holding them clamped upon the roller. 10

In testimony whereof I affix my signature in presence of two witnesses.

FRANK E. BONHAM.
